UNITED STATES PATENT OFFICE.

JOHN WALLACE NEFF, OF EASTON, PENNSYLVANIA.

SAFETY PAPER.

Application filed March 12, 1927. Serial No. 174,957.

This invention relates to improvements in safety paper and to a method for the manufacture of the same, and more particularly to safety paper for checks, bonds, notes and other negotiable and documentary paper.

The present invention has for its primary object the provision of a safety paper which is extremely sensitive to eradicating or bleaching substances or compounds applied to the paper in any manner, whereby such application results in ready and speedy discernment.

It is a further object of the present invention to provide a safety paper of the above character which is extremely sensitive to eradicating or bleaching solutions or compounds applied to the paper as a tracing over matter written or otherwise appearing thereon or applied for general eradication of matter appearing on the paper, and which thus offers protection against attempts to alter such matter appearing on the paper.

A further object is to provide in a safety paper a means to prevent alteration or removal of matter written or otherwise appearing thereon by the application of an eradicating compound or substance.

A further object is to provide a safety paper having normally invisible properties therein, which are rendered visible upon the application of an eradicating agent to thereby indicate an attempt to alter matter printed, written or otherwise appearing on the paper, which properties are not discernible before the attempt at alteration and which are retained indefinitely in the paper.

A further object is to provide in a safety paper a means of detection of fraudulent alteration, which means may be inexpensively applied to the paper at any stage of its manufacture with equal efficiency and utility resulting therefrom.

A further object is to provide an improved method of manufacturing a safety paper which is extremely sensitive to eradicating or bleaching compounds, solutions or substances, to thereby protect the user of the paper from attempts at fraudulent alterations of the paper by the application of such eradicating compounds or solutions.

Other objects will be in part obvious from the annexed drawing and in part indicated from the following analysis of the inven-

tion, in which reference is made to the accompanying drawings illustrating one embodiment of my idea.

In the drawings

Fig. 1 represents a negotiable paper, such as a check, protected in accordance with my invention.

Fig. 2 represents the check shown in Fig. 1 after the application of an eradicating agent for alteration purposes.

My invention consists broadly in applying to the paper to be protected in any approved manner, as by subjecting the paper to a bath, a coating of a chemical solution which is colorless upon application to the paper; and thereafter, while the paper is wet, impressing or accentuating thereon with a printing roller or the like, suitable warning indicia such as the words "Void". Contact between the impression surface of the roller and the paper wet with the chemical solution, causes the solution to be pressed more densely on the surface of the paper engaged by the impression surface than on the surface of the paper not contacted with by said impression surfaces. Both the coating of the solution applied to the paper and the impressed warning indicia formed therewith are normally invisible. Upon the application of a chemical designed for alteration purposes, such as the so-called ink eradicator, a chemical reaction is set up which causes a change of color of the paper affected thereby, the warning indicia appearing in a relatively darker color by reason of its more dense application to the paper caused by contact with the impression surface of the roller, while the parts of the paper not affected by the pressure of said roll, altho subjected to the bath, and forming a background for the warning indicia, appear in a relatively lighter color, but of sufficient depth to be readily distinguished from the normal or unchanged color of the paper. The warning indicia is thus readily discernible against a field of relatively lighter color, and both the indicia and its field or background are rendered visible upon the application of an eradicating agent.

Any chemical solution or compound, which when applied to the paper is invisible but which is visibly reactive to eradicating or bleaching agents to cause an ineradicable impression or change of appearance in

the paper upon the application of an eradicating or bleaching agent, may be applied to the paper in accordance with the above, and any such solution or compound is included 5 within the scope and spirit of my invention.

In my prior Patent, No. 1,578,908, dated March 30, 1926, and in my co-pending application, Serial No. 171,269, filed February 26, 10 1927; I have described a satisfactory solution for the above purpose, namely, a colorless aniline solution, such as an aniline-chloride compound ($C_6H_5NH_2HCl$) or, as more 15 commonly designated, aniline-chloride or aniline salt. To the end that this solution is rendered stable and lasting when applied to the paper, I propose to make the solution slightly acid by adding thereto a small quantity of a suitable acid, such as citric, lactic, 20 or stearic acid. The proportions of the chemicals making up this solution are unimportant so long as the paper is thoroughly coated or impressed therewith.

In the drawings, numeral 5 represents a 25 safety paper, such as a check, to which has been applied as by a bath process, a coating of a colorless chemical solution, such as the aniline chloride compound hereinbefore noted. The paper while still wet has been 30 brought in contact with a printing or "dandy" roll having an impression surface thereon adapted to impress suitable warning indicia, such as the words "Void" throughout the paper and with the solution 35 just previously applied to the paper. The pressure of the impression surfaces of the roll on the wet paper causes the solution to be more densely applied to the contacted surface of the paper than to the rest of the 40 paper in such a manner as to be readily seen, if the paper were subjected to an ink eradicating fluid, against the field or background resulting from the coating or bath of the paper. The numeral character 6 designates 45 the field or background for suitable warning indicia, such as the words "Void" indicated at 7, and impressed thereon by a printing or dandy roll or the like, the dotted lines indicating that the indicia and its field 50 are normally invisible. The printing surface of the roll, if desired, might be "inked" with the colorless chemical solution which in effect would superimpose the warning indicia on the coating applied to the paper with the 55 solution as above described. Similarly, the pressure of the impression surface of the roll may be regulated, and may impress the warning indicia into the body of the paper without unduly destroying the finish of the 60 paper. The solution and/or the warning indicia may be applied throughout the whole surface of the paper or may be applied to only those parts of the paper upon which is written or otherwise impressed matter sub- 65 ject to alteration.

In Fig. 2, I have illustrated the result of an attempt at alteration, and it will be assumed that an eradicating agent such as an ink eradicator has been applied to the check for the purpose of alteration or removal of matter written thereon. The 70 eradicating fluid causes with the applied coating a chemical reaction which produces what is commonly known as "aniline black". The impressed or accentuated warning indicia, by reason of the more thorough impregnation of the solution on the paper caused by contact with the impression surface of the dandy roll, appears in a pronounced black or dark brown color, as indicated at 8, against the field or background 9 which has similarly changed in color but to a lighter shade of brown. The word or words "Void" are rendered clearly discernible against the lighter background and 75 serve to nullify the paper. The "aniline black", being once established and brought out in the paper, can be removed or destroyed only by boiling the paper in sulfuric acid which would, of course, destroy 80 the paper.

Where an attempt is made to remove matter written or otherwise appearing on the check, such as the payee's name or the amount of the check, by tracing this matter with an eradicating fluid, there results the chemical reaction above noted with the applied invisible field or the invisibly impressed warning indicia, and the written matter traced over appears in black or brown color. The matter sought to be removed is consequently brought out in permanent and ineradicable form.

The addition of the citric or other named acids is not essential to my invention, but adds to the stability of the aniline-chloride compound on the paper when exposed to air or other elements for a long time. So, also, I do not wish to be limited to the use of aniline-chloride applied to the paper, as any colorless aniline solution, or any other chemical solution which, upon the application of eradicators, would produce an ineradicable impression, would function as 105 efficiently. A fugitive tint design may be applied as desired over the paper in order to provide a means of detecting frictional erasures by rubber, knife, or the like.

It is seen from the above that my improved safety paper and the method of producing the same presents many advantages over types and manufacture of safety paper now in use. The invention can be applied to any kind of paper with equal facility, as no special paper is needed, and, when applied, cannot be discerned. Paper protected in accordance with the above disclosure offers a high degree of protection against removal and/or alteration of matter printed, written or otherwise appearing on the paper. 130

- In manufacture and preparation, it is evident that the background can be applied by any well known coating or bath process and the warning indicia subsequently applied thereto by the usual printing or dandy rolls, such as are now in use for the purpose of applying the fugitive tint designs which are used in the manufacture of almost all safety papers. In the present invention, however, the dandy roll is engraved with the words "Void" or "Cancelled" or any warning indicia, instead of the designs commonly used, and the impression made on the paper is normally invisible instead of normally visible as the fugitive tints would appear. The above described process, however, does not necessarily obviate the application of a visible fugitive tint design to my safety paper, as the fugitive tint may be applied to take care of frictional erasures with rubber, knife, glass pencil, or the like. No new types of machinery are, therefore, necessary. The aniline solution can be applied at any time during the preparation of the paper, and could even be applied to a finished paper without injury or discernment of the same.
- It will be seen that the several objects of the invention are achieved and other advantageous results attained. As many changes could be made in carrying out the above invention, it is intended that all matter contained in the above description or shown in the accompanying drawing shall be interpreted as illustrative and not in a limiting sense.
- I claim:
1. The method of making safety paper which consists in applying to the paper a colorless chemical solution which is visibly reactive to bleaching or eradicating agents and accentuating warning indicia on said paper with said solution while the paper is wet with said solution, which warning indicia, if discernible, would inherently nullify the paper.
  2. The method of making safety paper which consists in applying to the paper a colorless chemical salt solution which is visibly reactive to bleaching or eradicating agents and impressing or accentuating warning indicia on said paper with said solution while the paper is wet with said solution, which warning indicia, if discernible, would inherently nullify the paper.
  3. The method of making safety paper which consists in applying to the paper a colorless aniline salt solution which is visibly reactive to bleaching or eradicating agents and impressing warning indicia on said paper with said solution while the paper is wet with said solution, which warning indicia, if discernible, would inherently nullify the paper.
  4. The method of making safety paper which consists in applying to the paper a
- colorless aniline compound which is visibly reactive to eradicating or bleaching agents and impressing or accentuating warning indicia on said paper with said compound while the paper is wet therewith, which warning indicia, if discernible, would inherently nullify the paper.
5. The method of making safety paper which consists in applying to the paper a colorless chemical solution which is visibly reactive to bleaching or eradicating agents, impressing warning indicia on said paper with said solution, and stabilizing the same by the addition of a small quantity of acid to said solution.
6. A safety paper having applied thereto a colorless chemical compound which is visibly reactive to eradicating agents, and warning indicia impressed on the paper with said compound, the applied compound adapted to form a visible background on the paper for the impressed indicia.
7. A safety paper having applied thereto a colorless chemical salt compound which is visibly reactive to eradicating or bleaching agents, and warning indicia impressed on the paper with said compound, the applied compound adapted to form a visible background on the paper for the impressed indicia.
8. A safety paper having applied thereto a colorless aniline salt compound which is visibly reactive to eradicating or bleaching agents, and warning indicia impressed on the paper with said compound, the applied compound adapted to form a visible background for the impressed indicia.
9. A safety paper having applied thereto a colorless aniline chloride compound which is visibly reactive to eradicating or bleaching agents, and warning indicia impressed on the paper with said compound, the applied compound adapted to form a visible background for the impressed indicia.
10. A safety paper having applied thereto a colorless chemical compound which is slightly acid and visibly reactive to eradicating agents, and warning indicia impressed on the paper with said compound, the applied compound adapted to form a visible background for the impressed indicia.
11. A safety paper having applied thereto a colorless chemical compound which is visibly reactive to bleaching or eradicating agents, and warning indicia impressed on the paper with said compound, the applied compound adapted to form a visible background against which the impressed indicia are discernible.
12. A safety paper having applied thereto a colorless chemical salt compound which is visibly reactive to bleaching or eradicating agents, and warning indicia impressed on the paper with said compound, the applied compound adapted to form a visible back-

- 4
- ground against which the impressed indicia are discernible.
13. A safety paper having applied thereto a colorless aniline salt compound which is visibly reactive to bleaching or eradicating agents, and warning indicia impressed on the paper with said compound, the applied compound adapted to form a visible background against which the impressed indicia are discernible.
14. A safety paper having applied thereto a colorless aniline chloride compound which is visibly reactive to bleaching or eradicating agents, and warning indicia impressed on the paper with said compound, the applied compound adapted to form a visible background against which the impressed indicia are discernible.
15. A safety paper having applied thereto a colorless chemical compound which is slightly acidic and reactive to bleaching or eradicating agents, and warning indicia impressed on the paper with said compound,
- the applied compound adapted to form a visible background against which the impressed indicia are discernible.
16. The method of making safety paper which consists in applying to the paper a colorless chemical solution which is visibly reactive to bleaching or eradicating agents, and impressing warning indicia on said paper with said solution, which indicia, if discernible, would inherently nullify the paper.
17. The method of making safety paper which consists in applying to the paper a colorless chemical salt solution which is visibly reactive to bleaching or eradicating agents, and impressing warning indicia on said paper with said solution, which indicia, if discernible, would inherently nullify the paper.

Signed at Easton, Pennsylvania, this 7th day of March, 1927.

J. WALLACE NEFF.
